STADIUM ROOF

Alexander G. Tarics, Belvedere, Calif.
(1019 Market St., San Francisco, Calif. 94103)

Filed Dec. 28, 1970, Ser. No. 26,674

Term of patent 14 years

Int. Cl. D25—99

U.S. Cl. D13—1 R

FIG. 1.

FIG. 2.

FIG. 3.

FIG. 4.

FIG. 1 is a perspective view of the top of a stadium roof showing the design of my invention;

FIG. 2 is a side elevational view of the stadium roof of FIG. 1 enclosing a stadium indicated by a dotted line, the latter being included for illustrative purposes only and forms no part of the claimed design for a stadium roof;

FIG. 3 is a sectional view of the stadium roof of FIG. 1 taken along a vertical plane; and

FIG. 4 is a fragmentary view of the stadium roof of FIG. 1 taken along the plane indicated at 4-4 in FIG. 3.

I claim:

The ornamental design for the stadium roof, as shown and described.
